UNITED STATES. PATENT OFFICE.

HENRY C. MAGRUDER, OF RICHMOND, VIRGINIA.

CAR-COUPING.

SPECIFICATION forming part of Letters Patent No. 315,804, dated April 14, 1885.

Application filed February 18, 1885. (No model.)

To all whom it may concern:

Be it known that I, HENRY C. MAGRUDER, a citizen of the United States, residing at Richmond, in the county of Henrico and State of Virginia, have invented certain new and useful Improvements in Car-Couplers, of which the following is a specification, reference being had therein to the accompanying drawings.

This invention relates to certain new and useful improvements in car-couplers, and it is designed to be either automatic in its action or to be used in connection with the ordinary link and pin.

In the accompanying drawings, forming a part of this specification, and on which similar letters of reference indicate the same or corresponding features, Figure 1 represents a side elevation of a car with one of my improved coupling-hooks attached and one removed; Fig. 2, an inverted plan view thereof showing both coupling-hooks; Fig. 3, a plan view of two coupling-hooks as they appear after coupling, and Fig. 4 a detail side elevation of one of the coupling-hooks.

The letter A refers to the draw-bar of a car, situated in the present instance somewhat to one side of a central line passing longitudinally through the car, and provided at its rear with an aperture, B, designed to receive one end of the rod C, which is surrounded by a spiral spring, D. This spring at one end abuts against the draw-bar A, and at the other bears against the collar, (forming the lower extension of the bracket E,) which fits around one end of the rod C.

The letter F refers to the forward portion of the draw-bar, and is provided with a slot, G, through which passes a pin, H, by which it is securely and slidingly connected with the body of the car. The rear portion is likewise provided with slots and pins similar to those just described. The forward portion, above mentioned, near its outer end is bored transversely to receive the bolt I, which passes therethrough and supports at either side thereof the coupling-hooks J. These hooks have arrow-heads, the barbs of which engage one another. Between these hooks and the nuts on the outer extremities of the bolts I place a washer, K, against which abuts one end of a spiral spring, L, surrounding the bolt, and

the other end of which spring bears against the nuts just mentioned.

The letter M refers to a bar which passes through the coupling-hooks (they having apertures for this purpose) a little above and slightly to one side of the bolt I, the purpose of which bar is to assist in supporting the heft of the coupling-hooks and to keep them in a horizontal plane. Each hook on its upper edge is provided with a staple, N, which receives the lower curved portion of the bail O.

Between the middle and upper portion of the car proper, and at either side of the center, are brackets P, the object of which is to receive and hold in place the transverse bar Q, the central portion of which is U-shaped and its ends or extremities formed into cranks R. Connection is made between the bail O and the U-shaped portion of the transverse bar Q by means of a rod, S, whereby, when the cranks are depressed, the hooks, through the medium of the rod S and the bail O, are elevated, and in this manner cars which are coupled are uncoupled.

It is to be observed that the coupling-hooks J, as seen in Fig. 4, are provided with a slot, T, the object of which is to receive a link, when it is desired to use this method of coupling, the pin being inserted in the aperture U in the usual manner. It is also to be observed that the draw-bar is mounted, as above described, somewhat to one side of a central line passing longitudinally through the car, the object of which is to bring the coupling-hooks on each car slightly to one side of the center, so as to permit of their passing by each other in the act of coupling. It is further to be observed that the forward portion of the draw-bar, at its point of connection with the draw-bar proper, is cut away and made somewhat smaller than at its outer extremity, and that the spiral springs interposed between the washers and the nuts on the bolt I allow the hooks to be expanded, which becomes necessary when an opposite hook is forced between them, and the cut-away portion allows the respective rear ends of the hooks to near each other during the entrance of the opposite coupling-hooks.

Having thus fully described my invention, what I claim as new, and desire to secure by Letters Patent, is—

1. In a car-coupler, the combination, with the draw-bar having its forward portion tapered near its point of connection with said draw-bar, and provided with an aperture near its forward end, the bolt, and the coupling-hooks provided with apertures and fitting on said bolt, of the springs interposed between the washer and the nuts, whereby the coupling-hooks are allowed to give during the entrance 10 of the opposite hook.

2. In a car-coupler, the combination, with the draw-bar and the coupling-hooks secured to said bar, of the rod extending through apertures in the coupling-hooks and above the draw-bar, whereby the hooks are kept in a horizontal plane.

3. In a car-coupler, the combination, with the draw-bar and the coupling-hooks secured thereto, and each provided with a staple, of 20 the bail, the rod, and the transverse bar having a U-shaped portion and cranks, whereby when the cranks are turned the coupling-hooks are elevated.

4. In a car-coupler, the combination, with 25 the draw-bar having an aperture, the rod fitting in said aperture and surrounded by a spring, the depending bracket having a collar

and supporting said rod, of the coupling-hooks provided with slots and apertures.

5. In a car-coupler, the combination, with the draw-bar and the coupling-hooks secured to said bar, and the rod extending through the apertures in the coupling-hooks and above the draw-bar, of the bail connected with the hooks, the rod, and the transverse bar having a U- 35 shaped portion and cranks, whereby when the cranks are turned the coupling-hooks are elevated.

6. In a car-coupler, the combination, with the draw-bar having an aperture in its forward portion, the bolt, the coupling-hooks having apertures, and the springs interposed between the washers and the nuts on the bolt, of the bail connected with the hooks, the rod, and the transverse bar having a U-shaped portion and cranks, whereby when the cranks 40 45 are turned the coupling-hooks are elevated.

In testimony whereof I affix my signature in presence of two witnesses.

HENRY C. MAGRUDER.
